UNITED STATES PATENT OFFICE.

JONAS NORTHRUP, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

FEELER LOOM.

Application filed April 30, 1927. Serial No. 187,817.

The present invention relates to feeler looms, and more particularly to mechanism for controlling the operation of such looms by the filling feeler.

5 Feeler looms are controlled in their operation by the amount of filling on the bobbin in the shuttle; in some feeler looms the approaching exhaustion of the filling causes weft replenishment, and in others it causes 10 stopping of the loom to enable the operative to replenish the supply of weft. The illustrated embodiment of the present invention is a loom which is provided with mechanism for stopping it in anticipation of complete 15 exhaustion so that the filling shall not fail before the loom stops. This method of controlling the loom obviates the exhaustion of the filling during the pick, which would necessitate removal of the filling over a part 20 of the width of the cloth being woven, or over the entire width in case the filling extended from the one selvage across the warp and beyond the other selvage, but was ended before it reached the shuttle so that the 25 thread was not drawn into the shed under proper tension to make perfect cloth. The object of the invention is to improve looms of this type, and the invention consists in the construction hereinafter described and 30 particularly defined in the claims.

In the accompanying drawings illustrating the preferred form of the invention, Fig. 1 is an end elevation of a portion of a loom embodying the present invention; Fig. 2 is a view similar to that of Fig. 1 with some parts removed and with the mechanism occupying different positions; Figs. 3 and 4 are front views of a portion of the left-hand end of the loom with the parts in 40 different positions; Fig. 5 is a view similar to Fig. 1 with the parts in different positions; Fig. 6 is a view similar to Fig. 5 with some of the parts removed for the sake of clearness; Fig. 7 is a face view of the 45 groove block; and Fig. 8 is a horizontal section taken on the line 8-8, Fig. 6.

The illustrated embodiment of the invention is described as follows: The loom frame 10 supports the swords 11 carrying the lay 12 operated by the pitman 13 in the usual manner. The lay shaft 14 is supported in bearings carried by the frame. The bell crank lever 15, pivoted at 16 on the bracket 17, has a rearwardly extending arm 18 which

operates the clutch to start and stop the 55 loom. The bell crank lever 15 has a forwardly extending arm 20 connected by means of the link 21 with the lever 22 pivoted at 23 upon the frame of the machine. A spring 24 connected to the lower end of 60 the lever 22 normally tends to turn the lever into the position shown in Fig. 1. When the lever 22 occupies the position illustrated in Fig. 1, the clutch is open; when it is moved to the left of this position the 65 clutch is closed. The lever 22 is provided at its upper end with a T-slot 25 which receives a pin 26 secured in the end of the shipper lever 27 mounted on the shaft 28 supported in bearings in the frame of the 70 loom. When the shipper lever occupies the position shown in Fig. 1 the spring 24 tends to hold it there. When the lever 27 is pulled upon by the operative, the pin 26 swings the lever 22 to the left-hand position 75 and causes the clutch to be closed. The shipper lever 27, therefore, is available to open and close the loom clutch for starting and stopping the loom.

When the loom is stopped by opening the 80 clutch a brake is applied. The rod 30 is connected at its rear end to the brake mechanism and at its forward end to the bell crank lever 31, freely pivoted on the shaft 28. The upper end 32 of this bell crank lever 85 carries a roll 33 which is adapted to engage either one or the other of two depressions 34 or 35 in the disk 36, which is formed integral with the brake lever 37, pivoted at 38 on the frame of the machine. When the brake 90 lever is turned to present the recess 34 to the bell crank roll 33, it forces the brake rod 30 rearwardly and thereby releases the brake; when the roll 33 is received in the recess 35, the brake rod 30 is permitted to move forwardly and the brake is applied. The brake lever 37 is provided with a handle 40 for convenient use by the operator.

The swing jaw 41 is pivotally mounted at 42 on the brake lever 37. This swing jaw 100 is provided to secure cooperation between the shipper lever 27 and the brake mechanism, the shipper lever 27 being provided with a pin 43 which enters the space between the two arms of the swing jaw 41. The 105 width of the opening between the jaws is such that while the shipper lever is in its clutch-open position, as shown in Fig. 1, the

brake lever may be pulled forward by the operative to release the brake without movement of the shipper lever; but when both brake lever and shipper lever are in their rear positions, the projection 44 on the swing jaw is in contact with the projection 45 connected as described with the brake lever. The parts then occupy the position illustrated in Fig. 2, wherein the pin 43 is shown in the position which it occupies when the shipper lever is in the rear position and the clutch is open. Then pulling the shipper lever forward causes the pin 43 to move in the arc of a circle forwardly about the pivot 28 as a center until it strikes the forward arm 46 of the swing jaw, and thereby turns the brake lever 37 through the engagement of the projections 44 and 45. As soon as the roll 33 rides over the rise between the depressions 35 and 34, the pressure of the brake rod 30 on the roll causes it to force the roll 33 into the recess 34, thereby swinging the bell crank lever 31 in the direction to release the brake. The loom is then in running condition with the clutch closed and the brake free. In this position both clutch lever and brake lever are in forward positions. The stopping of the loom is initiated by moving the brake handle rearwardly. This movement may be performed by the operative and it causes the recess 35 to be presented to the roll 33 of the bell crank lever 31, thereby permitting the latter to swing to the left so as thereby to move the brake rod to the right and apply the brake.

After the first portion of the rearward movement of the brake lever 37 is completed, the front jaw 46 of the swing jaw strikes the pin 43 in the clutch lever and moves it rearwardly, thereby permitting the spring 24 to swing the lever 22 in the direction to pull the clutch link 21 forwardly so as thereby to open the clutch. The loom is thus stopped with the clutch open and the brake applied. If, now, it is desired to turn the loom over by hand, the operative will pull upon the brake handle and swing the brake lever forward and the parts will occupy the position shown in Fig. 1 with the clutch still open and the brake released.

Mechanism is provided controlled by a filling feeler for stopping the loom, and this is secured by the rearward movement of the brake lever. To this end the loom is provided with a filling feeler 50 adapted to enter the shuttle 51 through the hole 52 in the front of the shuttle box to feel of the thread upon the forward beats of the lay when the shuttle is in the box opposite the feeler. The feeler is connected with a feeler rod 53 which extends from the feeler proper to a trip lever 54, pivoted at 55 upon the bracket 56 secured to the loom by the screw 57. The feeler is provided with a spring,

as is usual with many types of feelers, normally acting to exert a pull on the rod 53 tending to move it in the direction of the arrow 58. This spring is prevented in the usual manner from exerting any pull upon the rod 53 at all times except when the filling feeler 50 is in engagement with the bobbin, and when filling is present the tendency of the spring to pull upon the rod is prevented by the filling. In the absence of filling, however, the spring exerts its pull upon the rod and moves it in the direction of the arrow 58, thereby swinging the lever 54 from the position shown in Fig. 3 to the position shown in Fig. 4. The lower end of the trip lever 54 is provided on its left-hand face with a projection 60. This projection 60 is adapted to engage a projection 61 on the bell crank or bunter lever 62. The parts are cut away in Fig. 6 to show the shape of this bunter lever 62, which is pivoted at 63 on the brake lever 37. When the loom is running, the projection 61 of the bunter lever 62 is supported by the projection 60 of the trip lever 54. When critical exhaustion is indicated, the rod 53 is pulled upon to swing the lever to the position shown in Fig. 4 as described. A stop pin 64 is provided on the bracket 56 to prevent the trip lever 54 from swinging to the right far enough to interfere with the operation of the brake lever 37.

The left-hand end of the bunter lever 62 is of such a weight that it tends to turn the lever on its pivotal support from the position shown in Fig. 1 to the position shown in Fig. 5. The lower end of the depending arm of the bunter lever 62 is provided with a widened portion 65, which on its right side, as viewed in Fig. 4, rests against the surface 66 of the bracket 67, bolted at 68 to the frame of the machine. This bracket carries at its lower end two arms 70 and 71, in which is supported the shaft 72. Pivotally mounted on this shaft is a groove block 73, having upwardly extended arms 74 and 75. A spring 76 engages the pin 77 at one end and the arm 71 of the bracket at its other end, and normally tends to turn the groove block in the direction to cause it to move to the right, as viewed in Figs. 3 and 4. This causes the arm 74 to be pressed against the widened end 65 of the bunter lever 62 when the latter occupies the position shown in Fig. 1. When the bunter lever 62 turns from the position shown in Fig. 1 to the position shown in Fig. 5, the groove block swings to the right from the position shown in Fig. 3 to the position shown in Fig. 4. This movement of the groove block is for the purpose of bringing it into engagement with a reciprocating part in order to cause the latter to be moved into position to engage the widened end of the bunter lever 62. This reciprocating part is the bunter 78

mounted on the bunter carrier 80, which in turn is secured by the set screw 81 to the upper end of a reciprocating rod 82. This rod is secured at its lower end in the block 83, pivotally mounted at 84 on the arm 85 secured on the lay shaft 14 by means of the set screw 86. The rod 82 is thus moved up and down with the movements of the lay. As the lay moves forwardly the rod 10 lowers, and as the lay moves rearwardly the rod rises.

The bunter carrier 80 is provided with a laterally projecting tooth 87 (see Fig. 8), which is adapted to engage a groove formed 15 in the adjacent surface of the groove block 73. The bunter carrier 80 and the rod 82, being pivoted at 84 upon the arm 85 secured to the lay shaft 14 and extended slightly forwardly beyond the pivot 84, tend normally to swing by gravity to the position occupied in Figs. 1, 2 and 5. When the groove block is permitted, however, to move to the right, as viewed in Fig. 3, the tooth 87 engages the groove 88 in the groove block 20 at the right-hand end of the groove as the groove block is viewed in Figs. 5, 6 and 8, and at the left-hand end of the groove as viewed in Fig. 7, at a point in the neighborhood of the place indicated by the reference 25 character 90. Assume that the tooth engages the groove at the point 90, upon the next upward movement of the tooth 87 it moves upward in the groove to the point 91. At 92, however, there is a ledge in the 30 groove, so that when the tooth moves downwardly again it cannot return to the point 90 and is obliged to move down through the portion of the groove at 93 and drop off the ledge at 94, thereby finding itself in the 35 lower portion of the groove 95. Successive reciprocations of the bunter carrier thereby advance the bunter toward the left from the position shown in Fig. 5 to the position indicated in Fig. 6, the path of movement of 40 the tooth of the bunter carrier being along a saw-tooth path upward on one incline, downward on the next incline and repeat, thereby bringing the bunter below the lower end of the bunter lever 62, as shown in Fig. 45 6; whereupon, on the next upward movement, the bunter will strike the lower end of the bunter lever 62 and force it bodily upward, thereby transmitting a force to the 50 brake lever 37 which will cause it to move from its forward position toward its rear position, that it is to say, from the position shown in Fig. 6 to a position substantially that shown in Fig. 2. Before the brake lever reaches the position in Fig. 2, however, 55 the bunter lever 62 will be free from the bunter and will tend to turn to the position shown in Fig. 2, but it will not reach that position until the groove block is lifted off the tooth of the bunter carrier. The bunter lever 62 will be held from swinging to the

position shown in Fig. 2 by the engagement of its widened lower end with the inwardly curved arm 75, which, as shown in Fig. 4, prevents the bunter lever 62 from swinging beyond engagement with such arm. So it is 70 that the bunter lever 62 is held from tipping to the position shown in Fig. 2 until the groove block is moved away or lifted so as to permit such movement. The operative will now replenish the supply of filling in 75 the shuttle and then start the loom again. This forward movement of the brake lever will cause the return of the bunter lever 62 to the position shown in Fig. 1, thus automatically lifting the groove block off of 80 the widened lower end of the lever, and at the same time freeing the bunter carrier, which will move back to its right-hand position, as shown in Fig. 1.

This apparatus is particularly intended to 85 delay the stopping of the loom after approximate exhaustion of the filling in the bobbin three picks, so that indication of approaching exhaustion is given while there is still sufficient filling on the bobbin for 90 three picks of the shuttle across the loom, and thereupon the loom stops.

The invention is adapted for use in connection with a filling supply loom wherein filling replenishment is indicated a certain 95 number of picks prior to actual replenishment, and so it will be understood that some of the claims are to be read and understood as generic to changing the operation of the loom, whether by stopping it or by weft 100 replenishment.

More specifically the invention contemplates a feeler loom stop mechanism having provision for stopping the loom a certain 105 number of picks after filling exhaustion is indicated.

Having thus described the invention, what is claimed is:

1. A feeler loom having, in combination, 110 a lay, a shuttle, a feeler mounted to enter the shuttle and detect the condition of the filling, a trip lever connected with the filling feeler, a shipper lever for starting and stopping the application of power to the loom, a brake lever for applying a braking force to the 115 loom, connections between the shipper lever and the brake lever having provision for throwing off the brake when the shipper lever is moved to starting position, and for throwing off the shipper lever when the 120 brake is applied, and delay-action means under the control of said trip lever for applying the brake and shifting the shipper to disconnect the power.

2. A feeler loom having, in combination, 125 a lay, a shuttle, a feeler mounted to enter the shuttle and detect the condition of the filling, shipper mechanism, brake mechanism, a reciprocating bunter, and connections between the brake mechanism, the shipper 130

mechanism and the feeler constructed to operate automatically upon the exhaustion of the filling to a predetermined point to bring the reciprocating bunter and the part connected with the brake mechanism into operative relation so that thereby, after filling exhaustion is finally indicated, the brake will be applied, the shipper thrown to disconnect the power, and the loom will be stopped.

3. A filling feeler loom having, in combination, a lay, a shuttle, a filling feeler mounted to enter the shuttle and detect the condition of the filling, loom controlling means, a reciprocating bunter, and connections between the filling feeler, the loom controlling means and the bunter acting automatically upon the exhaustion of the filling to a predetermined point to cause a part of the loom controlling means to strike and move the bunter along its reciprocatory path sufficiently to cause a change in the operation of the loom.

4. A loom having, in combination, a lay, a shuttle, a feeler for feeling of the filling in the shuttle, loom controlling means, and a bunter normally reciprocating in a certain path of motion, the loom controlling means having provision upon the predetermined exhaustion of filling in the shuttle to engage the bunter and move it step by step from an inoperative position to an operative position with respect to the loom controlling means so as thereby to cause operation of the latter at a predetermined interval after filling exhaustion is indicated.

5. A loom having, in combination, a shipper lever, a filling detector, shipper operating devices comprising a groove block normally held by the shipper operating devices out of operation, and a reciprocating bunter provided with a tooth adapted to engage a groove in the groove block and to be itself moved thereby upon indication of filling exhaustion to cause delayed stopping of the loom.

6. A loom having, in combination, a bunter, a device adapted to be engaged by the bunter for causing a change in the operation of the loom, and means for moving the bunter comprising a groove block and adapted to engage a part connected with the bunter to move the latter laterally to cause actuation of the loom controlling means.

55. 7. A feeler loom having, in combination, a lay, a shuttle, a filling feeler, loom controlling means, a device for operating the latter comprising two parts, a bunter, and a bunter moving device the one being provided with a tooth and the other with a groove, reciprocations of the bunter causing the movement of one into position to cause actuation of the loom controlling device by the bunter.

65. 8. A feeler loom having, in combination,

a lay, a shuttle, a filling feeler for feeling of the filling in the bobbin, loom controlling devices adapted to be actuated to cause a change in the operation of the loom, mechanism for actuating the loom controlling devices comprising a reciprocating bunter having a tooth, and a pivoted groove block normally held out of engagement with the tooth, the loom controlling devices having provision under the control of the feeler for permitting the groove block to engage the tooth, the groove block being provided with a saw-tooth groove acting upon reciprocations of the bunter to cause the latter to move laterally into position to operate the loom controlling devices.

9. A feeler loom having, in combination, a lay, a shuttle, a filling feeler, shipper mechanism comprising a shipper lever, and brake mechanism comprising a brake lever, the brake lever being provided with a swing jaw pivotally mounted upon the brake lever for rocking movement thereupon and the shipper lever being provided with a pin located between the arms of the swing jaw to engage said arms so that a movement of the shipper lever to start the loom will release the brake, and so that movement of the brake lever to apply the brake will operate the shipper lever to disconnect the power.

10. A feeler loom having, in combination, a lay, a shuttle, a filling feeler, a brake lever, a bunter lever on the brake lever, a trip lever connected with the filling feeler and adapted to cooperate with the bunter lever on the brake lever to support the bunter lever in operating position, a reciprocating bunter having a normal path of movement out of register with the bunter lever and provided with a tooth, a groove block provided with a groove normally held out of engagement with the tooth on the bunter by the bunter lever constructed and arranged so that predetermined exhaustion of filling causes a movement of the trip lever which thereby frees the bunter lever and permits the latter to move, and in turn releases the groove block and causes it to engage the tooth on the bunter, which is thereby, during the next few reciprocations thereafter, caused to move into engagement with the bunter lever which is thereby actuated, shipper mechanism, brake mechanism, and connections between the bunter lever and the shipper and brake mechanism to cause the throwing of the shipper and the application of the brake to stop the loom.

11. A feeler loom having, in combination, a lay, a shuttle, a filling feeler, a trip lever connected with the filling feeler, a brake lever, a bunter lever pivotally mounted on the brake lever and having a part adapted to be held in a certain position by the trip lever, a swing jaw pivotally mounted on the brake lever, a shipper lever having a pin adapted

- to be received in the opening of the swing jaw, brake mechanism, and means carried by the brake lever for actuating the brake mechanism.
- 6 12. A device for use on looms for delaying an indicated operation having, in combination, a reciprocating part provided with a tooth, a groove block provided with a groove adapted to cooperate with the tooth, 10 means for holding the groove block out of engagement with the tooth of the reciprocating part having provision, upon indication of a change in loom operation being required, to move in a direction to permit the 15 movement of the groove block into engagement with the tooth of the reciprocating part, and the groove block acting to move the reciprocating part laterally upon each reciprocation of the part.
- 20 13. A loom having, in combination, loom controlling means, a reciprocating part for changing the operation of the loom through the intervention of the loom controlling means comprising a reciprocating part and 25 a groove block, the reciprocating part and the groove block being provided, the one with a tooth and the other with a groove, means for causing the parts to be engaged upon the indication of a change being required in the operation of the loom acting 30 to move one of the parts laterally with respect to the other so as thereby to bring the reciprocating part into position to initiate operation of the loom controlling mechanism. 35
14. A device for use on feeler looms having a feeler and loom controlling devices comprising a reciprocating part and a block, the block and reciprocating part having, the one a groove and the other a cooperating tooth normally held from cooperation but permitted to cooperate upon the indication of a change in the operation of the loom being required, having provision for moving laterally one of the two cooperating members to bring a part into position to cause initiation of the operation of the loom controlling mechanism. 40
15. A loom having in combination, a lay, a filling detector, loom controlling means, 45 and a delay action device for said controlling means and under the control of the filling detector, including a reciprocating part having a projecting tooth, a block having a saw tooth groove adapted to receive 50 said tooth and formed to permit progress of the tooth through said groove in one direction only with the movement of the reciprocating part. 55

In testimony whereof I have signed my name to this specification.

JONAS NORTHRUP.
